Martin J. Herzler, INVENTOR
BY Joseph Fiedersheim, ATTORNEY.

ATTORNEY.

UNITED STATES PATENT OFFICE.

MARTIN J. HERZLER, OF BELLEVILLE, ILLINOIS.

WASHING-MACHINE.

SPECIFICATION forming part of Letters Patent No. 498,115, dated May 23, 1893.

Application filed February 8, 1892. Serial No. 420,651. (No model.)

To all whom it may concern:

Be it known that I, MARTIN J. HERZLER, a citizen of the United States, residing at Belleville, county of St. Clair, and State of Illinois, 5 have invented a new and useful Improvement in Washing-Machines, which improvement is fully set forth in the following specification and accompanying drawings.

My invention relates to improvements in the 10 class of washing machines which are adapted to swing or rock, and consists of novel means for retaining the lid of the tub in position.

It also consists in providing the tub with a removable supporting device.

15 Figure 1 represents a perspective view of a supporting device for a washing machine, embodying my invention. Fig. 2 represents a perspective view of the machine and support therefor in operative position.

20 Similar letters of reference indicate corresponding parts in the two figures.

Referring to the drawings:—A designates the tub of a washing machine, and A' designates a stand on which is supported the gudgeons B, B', to which are secured hangers C, C', the latter having fastened to them at 25 their lower ends the bar D, which is adapted to pass under the tub and assist in supporting the same. Secured to the bar D, is the cross piece E, which is provided with shoulders F, F' at its ends for retaining the tub in 30 position, and in a measure supporting the same. Loosely fitted on the gudgeon B, is a rod G, which is adjustably fastened by means 35 of its threaded end to one end of the bar H above the same, the other end of said bar having the rod G' connected with it in a similar manner, the lower end of said rod G' being provided with a hook G², which is fitted on 40 the gudgeon B', and as is evident may be easily removed therefrom.

J designates the lid of the tub, the same being shouldered so as to provide a tight joint with the tub, and prevent any leakage there-

from. Any suitable device for controlling the 45 lid is attached to the bar H. In the present case the same consists of a screw K which tightens against the said lid and holds it securely in position. I also employ hinged latches L, for connecting the lid with the tub, and prevent 50 improper displacement of the former. The upper ends of the rods G, G', are threaded so as to permit the adjustment of the bar H thereon.

The operation is as follows:—The screw is 55 loosened, the rod G' unhooked from the gudgeon B', and the bar H turned laterally, whereby the lid may be removed. The garments, &c., to be washed are now placed in the tub with sufficient water and soap, after which 60 the lid is applied, the bar and hooked rod are restored, and the screw tightened. Swing- 65 ing motions are then imparted to the tub in any suitable manner, whereby the garments, &c., will be thoroughly washed without any injurious effect, the machine being effective 70 in its nature, and of inexpensive construction.

Having thus described my invention, what I claim as new, and desire to secure by Letters Patent, is—

75 A washing machine consisting of standards, hangers with journals having bearings on said standards, a bar connecting the lower ends of said hangers, a cross piece connected with said bar and having shoulders on its upper side near the ends, a bar with rods adjustably connected with its ends, one of said rods being detachably connected with one of the hanger journals, and the other rod being 80 permanently connected with the other hanger journal a tub with a lid and a screw in said last mentioned bar bearing against said lid, said parts being combined substantially as described.

MARTIN J. HERZLER.
